UNITED STATES PATENT OFFICE.

GEORGE TAGGART, OF OLATHE, KANSAS, ASSIGNOR OF ONE-HALF TO
MICHAEL CLEARY, OF PAOLA, KANSAS.

STOP-BLOCK FOR BROKEN OR HEADLESS KNUCKLE-PINS.

SPECIFICATION forming part of Letters Patent No. 714,258, dated November 25, 1902.

Application filed June 3, 1902. Serial No. 110,035. (No model.)

To all whom it may concern:

Be it known that I, GEORGE TAGGART, a citizen of the United States, residing at Olathe, in the county of Johnson and State of Kansas, 5 have invented certain new and useful Improvements in Stop-Blocks for Broken or Headless Knuckle-Pins, of which the following is a specification.

My invention relates to that class of car-couplers of the "Janney" type equipped with means to support broken knuckle-pins, and thereby effect an equal distribution of strain on both parts of the pin and both arms of the coupler.

15 The object of my invention is to produce as a part or attachment to the coupler a stop-block having a shelf whereon the knuckle-pin may rest and an opening vertically below the pin through which a bar or rod may be passed 20 to force the pin upward out of the coupler.

To this end the invention consists in certain novel and peculiar features of construction and combinations of parts, as hereinafter described and claimed, and in order that the 25 invention may be fully understood reference is to be had to the accompanying drawings, in which—

Figure 1 represents a vertical section taken through the knuckle-receiving arms of the 30 coupler of the Janney type, the same being shown as equipped with means embodying my invention. Fig. 2 is an inverted plan view of a portion of the same. Fig. 3 is a detail perspective view, enlarged, of the pin-supporting device as preferably constructed when used as an attachment to an old coupler.

Referring now to the drawings in detail, where like reference-numerals designate corresponding parts, 1 designates a coupler of 40 any suitable or preferred type, and 2 the upper and lower knuckle-receiving arms thereof, said arms being perforated in the usual manner to receive the pin, hereinafter referred to. Depending from the lower arm at opposite sides of its pin-perforation are walls 3, these being designed to be cast integral with new couplers. The walls are preferably imperforate and are connected by a cross piece or shelf 5 at their lower ends, said cross-shelf 45 being centrally perforated, as at 6, with a

hole smaller than the diameter of the pin referred to below.

In the modification shown in Fig. 3 the walls 3 are preferably segmental, the space 7 between them corresponding to the space between walls 3 of Fig. 1. In said figure, also, one of the segmental walls is formed with a perforated arm 8, adapted to be attached by a screw-bolt (not shown) to the lower knuckle-receiving arm 2 of an old coupler. 55

9 designates a headless knuckle-pin, the same extending down through arms 2 and the interposed knuckle 10 of the coupler, the pin resting at its lower end upon the shelf 5 between the walls 3 and directly over the hole 6. 65 A spring-cotter 11 may be secured in the lower end of the pin, the space between walls 3 being to enable the cotter to be secured in or removed from position.

In Fig. 4 the cotter or its equivalent is absolutely necessary, as in said figure its prime function is to prevent descending movement of the pin. 70

From the foregoing it will be seen that the breakage of the pin, which frequently occurs, 75 will not be followed by the dislodgement of either part, nor will such breakage impose all of the strain upon either of the walls 2. It will, however, be applied by the two sections of the pin upon both walls, and as a result the 80 period of service of the coupler will not be shortened.

When the car arrives at a point where it is convenient to replace the broken pin by a new one, the trainman can remove the pin by 85 first removing the cotter and forcing the pin upward, introducing a rod through the hole 6 for this purpose.

It will thus be seen that I have produced what I prefer to call a "stop-block" for broken 90 and headless knuckle-pins, which embodies the feature of advantage enumerated as desirable and which as an attachment can be easily and quickly applied to old couplers and which when cast as an integral part of 95 the couplers will increase the cost of the latter but little more than the market value of the extra iron used. It will also be apparent that said stop-block is of simple, strong, and durable construction and may be varied in 100

minor particulars without departing from the spirit and scope of the appended claims.

Having thus described the invention, what I claim as new, and desire to secure by Letters 5 Patent, is—

1. The combination with a coupler of the Janney type, and a headless knuckle - pin therein of the same size throughout its length; of a stop-block comprising two walls depending from the lower knuckle-arm at opposite sides of its pin-opening, and a shelf connecting the lower ends of these walls and passing completely below the pin, said shelf having a hole concentric with the pin's axis but smaller than its diameter, all as and for the purpose set forth.

2. The combination with a coupler of the Janney type, and a headless knuckle-pin

therein of the same size throughout its length; of a stop-block comprising two segmental walls depending from the lower knuckle-arm at opposite sides of its pin-opening and spaced at their adjacent edges, a shelf connecting the lower ends of these walls and passing completely below the pin, said shelf having a hole concentric with the pin's axis but smaller than its diameter, and a cotter standing within said space above the shelf and passing through the pin, and all as and for the purpose set forth. 20 25 30

In testimony whereof I affix my signature in the presence of two witnesses.

GEORGE TAGGART.
